PATENTED JUNE 16, 1863

Spec. 1764

Aug. Meiser's Design for the Coffee Service. ^{Patented June 16, 1863.} _{Aug. Meiser, Inventor.}

Des. 1764

Aloys. Meissel, of New York, N.Y.
Letters Patent No. 1764 dated June 16, 1863.

These specifications referred to in these Letters Patent and making part of the same

To all whom it may concern:

Be it known that I, Aloys Meissel, of New York,

2

Des 1764

in this County and State of New York, have invented or produced a new and original design for a "Tea and Coffee Service"; and I do hereby declare that the following is a full and exact description of the same.

In the accompanying drawing A, represents a Coffee pot. B the Sugar bowl. C the milk pot, D the Tea pot. E a cup and saucer, and F a coffee cup and saucer.

The nature of my invention consists in giving to the several parts forming the Service a polyhedral shape.

On the perpendicular edges, formed by the sides of the polygon, I make circular or oval indentations, a, forming concave surfaces.

The surfaces or indentations a, receive small ornamental figures which are either engraved in those surfaces or painted upon the same as represented in figure A.

In smaller pieces, the ornamental figures are placed upon the sides between the indentations a, as represented in figures C and E.

The largest piece, the Tea pot as represented by figure D, has the indentations a, as well as the surfaces between them, ornamented with figures representing flowers, which are either engraved or painted upon those surfaces.

What I claim as my invention, and desire to secure by Letters Patent is,

The design and form as above explained and as represented in the accompanying Drawing
